(74) Attorney, Agent, or Firm — Banner & Witcoff, Ltd.

(57) **CLAIM**

The ornamental design for a carafe lid, as shown and described.

DESCRIPTION

FIG. 1 is a front perspective view of a carafe lid showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken line showing of the various unshaded elements of the carafe lid represents unclaimed subject matter and forms no part of the claimed design.

1 Claim, 6 Drawing Sheets
